UNITED STATES PATENT OFFICE.

ARTHUR BRAGG, OF BROOKLYN, NEW YORK.

AMUSEMENT APPARATUS.

946,200.

Specification of Letters Patent. Patented Jan. 11, 1910.

Application filed April 12, 1909. Serial No. 489,256.

To all whom it may concern:

Be it known that I, ARTHUR BRAGG, a citizen of the United States, and residing at Brooklyn, in the county of Kings and 5 State of New York, have invented certain new and useful Improvements in Amusement Apparatus, of which the following is a specification, such as will enable those skilled in the art to which it appertains to make and use the same.

This invention relates to amusement apparatus of the class employed at summer resorts, amusement parks and other and similar places; and the object thereof is to 15 provide an improved apparatus of this class which is simple in construction and operation, and which is designed to amuse and entertain both old and young.

My invention involves an inclined track 20 or way and cars or carriages movable thereon by gravity in a manner similar to other apparatus of the same class, and the invention consists in the details of the construction of the track or way and the cars or 25 carriages hereinafter described and claimed, and by means of which novel, exciting and amusing results are produced.

The invention is fully disclosed in the following specification, of which the accompanying drawings form a part, in which the 30 separate parts of my improvement are designated by suitable reference characters in each of the views, and in which;—

Figure 1 is a sectional side view of a part 35 of the track or way and showing a car or carriage mounted thereon, Fig. 2 a sectional plan view of that part of the apparatus shown in Fig. 1 and on a smaller scale, Fig. 3 a longitudinal sectional view of 40 a part of an up-take employed in connection with the inclined track or way, and showing a car or carriage mounted thereon, Fig. 4 a transverse sectional view of a part of 45 the track or way and showing a car or carriage mounted thereon and in section, Fig. 5 a view similar to Fig. 4 but showing other parts of the construction, Fig. 6 a sectional side view of the construction shown in Fig. 5, Fig. 7 a sectional plan view similar to 50 that shown in Fig. 2 but on a smaller scale and showing a modification of the track or way and showing features of the construc-

tion shown in Figs. 2 and 5, and;—Fig. 8 a diagrammatic side view of the inclined track or way and indicating the up-take by which 55 the cars or carriages are conveyed from the bottom of the track or way to the top thereof.

My invention involves the use of an inclined track or way, and in Fig. 8 of the accompanying drawings I have indicated diagrammatically a side view thereof, the inclined track being indicated at a and the up-take by which the cars or carriages are conveyed from the bottom of the track or 60 way to the top thereof being indicated in dotted lines at a^2 . The inclined track or way, in the construction shown, is not continuous in one direction, but consists of a plurality of reversed inclines a^3 , and said 65 track or way may be substantially spiral in form, or it may consist of a plurality of reversed inclines the end portions a^4 of which are connected by circular or segmental loops. 70

In Fig. 1 of the accompanying drawings the bottom a^5 of the inclined track or way is shown substantially horizontal, and it will be understood that, in practice, short parts or reaches of said track or way may be horizontal if desired, the general inclination being sufficient to propel the cars or carriages over short spaces or reaches in the said track or way. The track or way consists of a bottom a^5 and side boards or guards a^6 , and I 80 also provide cars or carriages b adapted to travel on said track or way and which, in the form of construction shown, consists of a bed plate or frame b^2 mounted on rollers, 85 casters or similar devices b^3 which are adapted to rotate in the manner of ordinary casters, and which may be constructed in any desired manner. 90

The cars or carriages b are provided with seats, chairs or similar devices b^4 , and these 95 seats, chairs or similar devices are preferably provided with straps b^5 or other means for holding the occupants of said seats or chairs therein. The bed plate or frame b^2 of the cars or carriages b are also provided 100 around the edges thereof with wheels or rollers b^6 adapted to bear on the inner sides of the side boards or guards a^6 of the track or way, and said side boards

or guards a^6 are provided with buffer plates or strips a^7 with which said wheels or rollers b^6 come in contact in the operation of the apparatus, or in the operation of the 5 cars or carriages b in passing over the track or way. The transverse dimensions of the cars or carriages b are much less than the transverse dimensions of the track or way, and as the said cars or carriages pass downwardly over the track or way they are free 10 to move from one point to another transversely of the track or way or diagonally thereof, and in this operation the said cars or carriages come in contact with the side boards or guards a^6 at one side of the track or way and are deflected across the track or way, and this operation is repeated during the entire passage of the cars or carriages 15 downwardly over the track or way. In the 20 form of construction shown, the cars or carriages are oblong in shape and the corners thereof are cut away, but the plan of the said cars or carriages may be of any preferred form, and the said cars or carriages 25 may be round if desired. The track or way is provided at intervals with inclosed spaces forming closed chambers c , said chambers being formed by a top c^2 and end doors c^3 . The doors c^3 are hinged to the inner 30 sides of the side boards or guards a^6 of the track or way as shown at c^4 and are operated by the cars or carriages as they pass downwardly over the track or way, the doors at the upper end of the chambers c^6 being 35 forced inwardly while the doors at the lower end thereof are moved outwardly, and said doors are provided with springs c^5 which are secured thereto and to the track or way and which normally hold them in a closed 40 position.

Referring to Fig. 2 of the accompanying drawings, it will be seen that the buffer plates or strips a^7 which are secured to the side boards or guards a^6 of the track or way 45 are cut out at the points c^4 where the doors c^3 are hinged thereto, and said buffer plates or strips are provided above said hinge points with inwardly directed members a^8 against which the wheels or rollers b^6 of the 50 cars or carriages strike in the downward movement of said cars or carriages over the track or way, and which prevent the cars or carriages or the wheels or rollers b^6 from striking the edges of said doors that are 55 hinged to the side boards or guards a^6 . The closed chambers c are also provided with electric lights d which, in the form of construction shown, are suspended from the top thereof and provided with circuit wires 60 d^2 which are in electrical connection with a circuit making and breaking device d^3 operated by a transverse spring supported strip or plate d^4 placed on the bottom a^5 of the track or way, and as the cars or car-

riages pass through the chambers c the 65 wheels or rollers b^6 by which said cars or carriages are supported depress the strip or plate d^4 and complete the circuit through the wires d^2 to momentarily energize the light or lights d . Any desired number of 70 these lights may be employed, and the wires d^2 may be placed in connection with any suitable source of electrical supply.

The up-take a^2 of the inclined track or way a , or a part thereof, is shown in detail 75 in Fig. 3, and this up-take comprises a bottom e and side boards or guards e^2 , and the cars or carriages b are provided at one end thereof with attaching devices b^7 with which, in practice, may be connected a cable or 80 similar device f by means of which said cars or carriages are taken up over the up-take a^2 , this operation being the same as with other apparatus of this class. The up-take a^2 is also preferably provided centrally 85 thereof with a rack e^3 and the cars or carriages with a pawl e^4 which operates in connection with said rack and which will prevent the backward movement of the cars or carriages on the up-take a^2 if, at any 90 time, the cable f or its connections should be broken or thrown out of use. The bottom a^5 of the inclined track or way a may be smooth or even throughout all the portions thereof, or may be transversely corrugated 95 as shown at a^9 in Figs. 1 and 2, or part or all of said track or way may be undulated as indicated in Fig. 8. I have also shown at g a figure which represents a man and which is formed in connection with or attached to a transverse support g^2 hinged to the bottom a^5 of the track or way as shown at g^3 and provided with a spring attachment g^4 secured thereto and to the track or way or to one of the side boards or guards 100 a^6 thereof and which normally holds the figure g in an upright position, and as the cars or carriages pass downwardly over the track or way they come in contact with this figure and depress it into the position shown 110 at g^5 in Fig. 6 and as the car or carriages pass over said figure it is automatically raised into the position shown in Fig. 5. Any desired number of these figures may be employed, and they may be placed in any desired position on the track or way. These figures may be formed to exactly represent 115 a man in the act of walking across the track or way and when struck by the cars or carriages in the manner described a thrilling 120 and exciting result is produced.

Instead of a part or all of the track or way being undulated in a vertical plane as indicated in Fig. 8, the said track or way may be laterally undulated or curved as 125 shown in Fig. 7, or the said track or way may involve both of these features of construction if desired. The bottom a^5 of the

inclined track or way is preferably provided with a hole or recess a^{10} at the point where the figure or figures g are connected therewith, and this hole or recess is preferably of the same form or outline as said figure or figures and the part g^2 and is adapted to receive said figure or figures when depressed or knocked over by the car, and this hole or recess is closed by a plate 10 a^{11} secured to the bottom a^5 of the track or way; my invention is not limited to this particular construction, and various changes in and modifications of this and other details of the construction herein shown and described may be made, within the scope of the appended claims, without departing from the spirit of my invention or sacrificing its advantages.

Having fully described my invention, 20 what I claim as new and desire to secure by Letters Patent, is:—

1. An amusement apparatus comprising an inclined track or way and a car or carriage movable by gravity thereon, said track or way being provided with side boards or guards, and the car or carriage being of less transverse dimensions than said track or way, said car or carriage being also mounted on wheels or rollers, and said track or way being provided at intervals with transversely arranged doors having tensional devices by which they are held in a closed position, and said doors being adapted to be opened by the car or carriage as it passes 35 downwardly over the track or way.

2. In an amusement apparatus, an inclined track or way having side boards or guards, and a car or carriage adapted to move downwardly by gravity over said track or way, said car or carriage being of less transverse dimensions than said track or way, and said track or way being provided with a closed chamber or chambers formed by a top and transversely hinged 45 doors having tensional devices which hold them in a closed position and which are adapted to be opened by the car or carriage as it passes downwardly over the track or way.

3. An amusement apparatus comprising an inclined track or way and a car or carriage movable by gravity thereon, said track or way being provided with side boards or guards, and the car or carriage being of less transverse dimensions than said track or way, said car or carriage being also mounted on wheels or rollers, and said track or way being provided at intervals with transversely arranged doors having tensional devices by which they are held in a closed position, and said doors being adapted to be opened by the car or carriage as it passes 55 downwardly over the track or way, the car or carriage being also provided with later-

ally directed wheels or rollers adapted to 65 bear on the side boards or guards of the track or way.

4. In an amusement apparatus, an inclined track or way and a car or carriage adapted to move downwardly thereover by 70 gravity, said track or way being provided at intervals with figures which are normally held in an upright position and are adapted to be depressed by the car or carriage as it passes downwardly over the track or way, 75 and said track or way being also provided at intervals with transverse doors normally held in a closed position and adapted to be opened by the car or carriage.

5. In an amusement apparatus, an inclined track or way and a car or carriage adapted to move downwardly thereover by 80 gravity, said track or way being provided at intervals with figures which are normally held in an upright position and are adapted 85 to be depressed by the car or carriage as it passes downwardly over the track or way, and said track or way being also provided at intervals with transverse doors normally held in a closed position and adapted to be 90 opened by the car or carriage, and the bottom of said track or way or a part thereof being also transversely corrugated.

6. In an amusement apparatus, an inclined track or way and a car or carriage 95 adapted to move downwardly thereover by gravity, said track or way being laterally undulated and being provided with transverse doors which are normally held in a closed position and are adapted to be opened 100 by the car or carriage.

7. In an amusement apparatus, an inclined track or way and a car or carriage adapted to move downwardly thereover by 105 gravity, said track or way being laterally undulated and being provided with transverse doors which are normally held in a closed position and are adapted to be opened by the car or carriage, and said track or way being also provided at intervals with figures 110 which are normally held in a raised position and are adapted to be depressed by the car or carriage as it passes thereover.

8. In an amusement apparatus, an inclined track or way and a car or carriage 115 adapted to be moved downwardly thereover by gravity, said track or way being laterally undulated or curved and being provided at intervals with closed chambers having transverse doors which are adapted to be opened 120 by the car or carriage.

9. In an amusement apparatus, an inclined track or way and a car or carriage adapted to move downwardly thereover by 125 gravity, said track or way being provided with a closed chamber or chambers having hinged doors normally held in a closed position and adapted to be opened by the car or

carriage, and said chambers being provided with an electric light or lights normally in an open circuit adapted to be closed by the car or carriage as it passes through said chamber or chambers.

5 In testimony that I claim the foregoing as my invention I have signed my name in

presence of the subscribing witnesses this 10th day of April 1909.

ARTHUR BRAGG.
